[57] CLAIM

The ornamental design for a baking pan, as shown and described.

DESCRIPTION

FIG. 1 is a top perspective view of a baking pan, showing my new design;

FIG. 2 is a top plan view of FIG. 1;

FIG. 3 is a left end elevational view of FIG. 1, the right end elevational view being identically the same;

FIG. 4 is a right side elevational view of FIG. 1, the left side elevational view being identically the same;

FIG. 5 is a bottom plan view of FIG. 1;

FIG. 6 is a cross-sectional view taken along 6—6 of FIG. 2; and,

FIG. 7 is a cross-sectional view taken along line 7—7 of FIG. 2.

FIG. 1

FIG. 2

FIG. 3

FIG. 4

FIG. 5

FIG. 6

FIG. 7
